UNITED STATES PATENT OFFICE

EDWIN W. FUERST, OF TOLEDO, OHIO, ASSIGNEE TO CLOVERDALE SPRING COMPANY, OF BALTIMORE, MARYLAND

DESIGN FOR A BOTTLE

Application filed August 15, 1931. Serial No. 40,858. Term of patent 14 years.

To all whom it may concern:

Be it known that I, EDWIN W. FUERST, a citizen of the United States, residing at 965 Wall St., city of Toledo, in the county of Lucas and State of Ohio, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

EDWIN W. FUERST.
